MACHINE FOR SPRAY COATING HOLLOW ARTICLES

John H. Fridén, Maplewood, and William A. Abrecht, Union, N. J., assignors to The Sun Tube Corporation, Hillside, N. J., a corporation of New Jersey

Application March 29, 1945, Serial No. 585,520

15 Claims. (Cl. 91—44)

1

This invention relates to a coating machine and more particularly to a machine, mechanisms, and a system of apparatus for coating the interior of tubular bodies.

It is highly desirable and in many cases essential that the inner surface of various tubular bodies be coated with a film of requisite thickness of a suitable substance to prevent undesirable reactions from taking place between the tubular body and compositions that may be deposited therein. For example, many present day tubes for containing medicaments, tooth paste, shaving cream, and the like are made of alloys containing lead. Unless a suitable liner or coating of a protective film be placed between the inner wall of the tube and the substance stored therein, there is a danger of objectionable reactions taking place between the substance in the tube and the material of the tube itself.

This invention is concerned primarily with an arrangement of mechanisms and devices for quickly and effectively coating the inner surface of tubes, such as those mentioned above. To this end the instant invention includes a mechanism in the nature of a turntable comprising a base that is rotatable about an upright hollow shaft. A plurality of spaced upright hollow arms are carried by the base and arranged equidistant from the axis thereof. The rotary mechanism includes a series of passages each of which communicates with the interior of a corresponding hollow arm and is adapted to communicate with the interior of the hollow shaft during a portion of each complete revolution of the base about the shaft. A suitable coating material is supplied to the hollow shaft in a liquid state and flows into each arm during a corresponding predetermined portion of each revolution of the base. The upper end of each hollow arm is provided with a plurality of spaced passages establishing communication between the interior and exterior thereof and preferably arranged in a manner to jet the fluid material at an acute angle upwardly and laterally of corresponding radii of each arm. Each arm is adapted to receive a tubular body in the manner that the fluid jetted by way of the passages therein is sprayed against the inner wall of the tubes. The arrangement of these passages is such that the fluid material jetted therethrough tends to raise each tube slightly above the upper end of its carrying hollow arm and impart a rotary motion to each tube during the spraying operation. This insures complete coating of the inside of each tube.

From the rotary mechanism above discussed

5 the tubes are placed on suitable supports mounted on an endless conveyor that is movable in a tortuous path through an oven or housing. The housing is divided by a perforate partition into an upper and a lower compartment, the path of movement of the endless conveyor and the tubes carried thereby being in the lower compartment. A blower transmits a continuous stream of a heated gaseous medium, such as air, into the upper compartment. The heated gas passes downwardly through the perforate partition and heats the lower compartment, maintaining the tubes at a temperature above the melting point of the coating material. Excess coating material drains off the individual tubes and is collected in a sump provided in the bottom of the oven. A pump having a screened inlet is employed to transmit the thus collected coating material while still in liquid state to the exterior of the housing for reuse or disposal as desired.

10 20 25 30 35 40 45 50 55 60 65 70 75 80 85 90 95

The tortuous path of the endless conveyor through the housing and the time required for any portion of the belt to pass through the housing are such that upon emergence of individual tubes from the housing, excess coating material will have drained off leaving a relatively thin film of the same on the inner surface of each tube. A blast of cooling air may be used to cool the tubes after they leave the housing, if desired.

It is an object of this invention to provide mechanisms and devices for readily coating the interior of tubular bodies.

Another object of the invention is to provide a system for placing a relatively thin film of a suitable coating material on the internal surface of a tubular body.

A further object of the invention resides in coating the interior of tubular bodies with a suitable material on a mass production basis.

This invention has for a still further object the provision of apparatus of the character indicated that is simple in design, rugged in construction, and is capable of performing its intended functions in a trouble-free manner.

With the above and other objects in view, the invention comprises the devices, combinations, and arrangement of parts set forth in the following detailed description and illustrated in the annexed drawings of a preferred embodiment of the invention, from which the several features of the invention, together with the advantages attainable thereby will be readily understood by persons skilled in the art.

In the drawings:

Figure 1 is a plan view of an arrangement of

devices and mechanisms embodying this invention, partly in horizontal cross section and with parts broken away for better illustration;

Figure 2 is a view in vertical longitudinal section of the apparatus of this invention taken along line 2—2 of Figure 1;

Figure 3 is a vertical transverse sectional view taken along line 3—3 of Figure 2;

Figure 4 is an enlarged transverse sectional view taken along line 4—4 of Figure 1;

Figure 5 is an enlarged fragmentary view of a portion of Figure 1, partly in horizontal cross section for better illustration;

Figure 6 is a top plan view in enlargement of a tube supporting member;

Figure 7 is a central cross sectional view taken along line 7—7 of Figure 6;

Figure 8 is an enlarged perspective view of a cylindrical positioning member that is located substantially coaxial with and adjacent to the 20 tube supporting member of Figures 6 and 7;

Figure 9 is a horizontal cross sectional view taken along line 9—9 of Figure 8;

Figure 10 is an enlarged top plan view of a hollow arm depicted in Figure 4; and

Figure 11 is a cross sectional view taken along staggered line 11—11 of Figure 10.

Referring now to the drawings, wherein like reference characters denote corresponding parts throughout the several views, and more particularly, to Figures 1, 2, and 3, we have illustrated therein a housing or oven 10 consisting of a front side wall 11, a rear side wall 12, and end walls 13 and 14, a top wall 15, and a bottom wall, in the nature of a dished pan, 16. It will be observed that bottom wall 16 is inclined and formed so as to obtain a central sump 17. Also bottom wall 16 extends forwardly of front wall 11 and rearwardly of rear wall 12. As is depicted in Figures 1 and 3, the housing 10 is assembled into a unitary structure by means of various angle and channel beams, and is maintained in desired elevated position by a pair of end support frames 18 and 19. A vertical partition 20 that terminates above bottom wall 16 serves to define a wall of an end compartment 21 within housing 10. A horizontal perforate partition 22, secured to angle irons 23 (Figures 2 and 3), divides the remainder of the interior of the housing into an upper compartment 24 and a lower or conveyor compartment 25.

Disposed across end compartment 21 is an inclined heating unit, such as a steam radiator 26, through which steam at predetermined pressure is circulated in the usual manner. Positioned within end compartment 21 above steam radiator 26 is a blower 27 that includes a blower casing 28, having a pair of air inlets 29, an air outlet 30, communicating with upper compartment 24, and a pair of blower rotors 31 carried on a horizontal drive shaft 32. Blower drive shaft 32 extends through the front and rear side walls of the housing and is rotatably supported in bearings 33 and 34 mounted on angle brackets 35 and 36 that are attached to front and rear walls 11 and 12 respectively. A pulley 37 is affixed to and rotatable with the rear end of blower shaft 32 for imparting rotation to the blower shaft through the coaction of an open V-belt 38 and a drive pulley 39, secured to shaft 40 of an electric motor 41. Air or other appropriate gaseous medium is drawn into lower compartment 25 through openings 42 and 43 in front wall 11 and through openings 44 and 45 in rear wall 12. This air on coming in contact with steam radiator 26 is heated to the

desired temperature and is then introduced into blower 27 through inlets 29 and discharged by way of blower outlet 30 into upper compartment 24. From upper compartment 24 the heated air passes through perforate partition 22 into lower compartment 25 for the purpose of maintaining tubular bodies, which will be discussed further along, at a predetermined elevated temperature.

An endless belt or the like 46 (Figure 1) carries a series of equally spaced upstanding pins 47. Each pin is adapted to receive and support a tubular body 48, such as a collapsible ointment tube that is to be internally coated with a suitable material, by the devices of this invention. Belt 46 may pass downwardly through an opening 49 in the floor in the course of its movement and be returned through a similar opening (not shown). The tubular bodies 48 may be placed on pins 47 at a convenient location before they reach the housing.

The apparatus of this invention embodies at least one rotary mechanism or turntable device 50 for spraying a coating of a suitable material in a fluid state, such as a liquid wax, into individual tubular bodies 48. Two such rotary mechanisms are generally indicated in Figure 1 and illustrated in detail in Figures 3, 4, and 5. Each rotary mechanism includes a stationary substantially upright hollow shaft 51 secured to a cover plate 52 over dished pan 16 (Figure 4). An insert 53 is located in the low portion of the hollow of shaft 51 and is provided with a blind passage 54 that communicates with a conduit 55, which, in turn, communicates with a supply of the liquid wax or other coating material (not shown). Concentric with shaft 51 and spaced therefrom by a pair of sleeve members 56 and 57 is a rotary hub 58. Also concentric with shaft 51 and rotatable about the axis thereof is a sprocket wheel 59. A base or turntable 60 is secured to the lower end of hub 58, for rotation therewith. Base 60 is formed with a series of radial passages 61. A plurality of spaced upstanding hollow arms 62 is arranged equidistant from the axis of rotation of hub 58. The lower end of each arm 62 extends into base 60, is secured to the base by a screw plug 63, and communicates with a corresponding radial passage 64 through an aperture 65. A series of radial passages 65 extend through hub 58 and sleeve 56. Stationary shaft 51 is provided with a port 66 that communicates with passage 54 in insert 53 through a duct 67. As will be observed from an examination of Figures 4 and 5, fluid coating material supplied by conduit 55 is transmitted by passage 54, duct 67, port 66, and passages 65 to each radial passage 64, and thence through apertures 65 into corresponding hollow arms, during a predetermined portion of each complete revolution of base 60. With the arrangement illustrated the flow of the coating material into each tubular arm is prevented during the remaining portion of each complete revolution of the base. The upper end of each hollow arm 62 is closed but is provided with a plurality of spaced passages 70 so arranged as to direct coating material at an acute angle upwardly and laterally of corresponding radii of each arm, as shown in Figures 10 and 11. In other words, the liquid coating material is jetted through passages 70 in a manner that as a result thereof the jetted fluid tends to raise each tubular body 48 slightly above its arm 62 and simultaneously impart a twirling or rotary movement thereto. This results in a thorough spraying and coating of the inner surface of each tubular body 48.

Disposed above base 60 is a support 71 that is secured to the upper end of hub 58 and rotatable therewith. Pivotal connected to support 71 by means of pins 72 is a plurality of generally L-shaped levers 73 angularly spaced from each other and corresponding in number to the number of hollow arms 62. A hood 74 is fastened to each lever 73 by means of a strap 75 and screw 76. Each lever 73 also carries a hook-like element 77 for engaging a single helical spring 78 that is joined at its ends (not shown) to form a ring. Spring 78 is always in tension and tends to urge each lever 73 upwardly with respect to support 71 about its pivot end 72. A circular plate 79 is secured to the upper end of stationary shaft 51 and is provided with an integral depending cam member 80 which urges and maintains each lever 73 downwardly about its pivot pin 72 during a predetermined portion of each complete revolution of hub 58. And is best shown in Figure 4, cam member 80 permits spring 78 to maintain hood 74 at the left in raised position, that is to say, away from the upper end hollow arm 62. Cam member 80 simultaneously maintains hood 74 at the right in a position over the upper end of hollow arm 62 and tubular body 48 against the action of spring 78. In other words cam member 80 urges and maintains each hood 74 over its corresponding hollow arm 62 during a predetermined portion of each complete revolution of base 60 against the action of spring 78 and permits spring 78 to move each hood 74 away from the upper end of each arm 62 during the remainder of each complete revolution of the base. Cam member 80 is so constructed and arranged as to urge and maintain each hood 74 over its corresponding arm for at least the portion of each complete revolution of the base that the coating material is flowing upwardly through the arm and discharge passages 10 thereof. It is recommended that the design of cam member 80, lever 73, and hood 74 be such that the hood is spaced from tubular body 48 when it is in position over the tubular body, as shown at the right in Figure 4. This permits the fluid jetted through passages 70 to raise the tubular body and impart rotary movement thereto as indicated above.

Disposed within hollow shaft 51 is an electrical heating cartridge 81 having a pair of electric leads 82 for connection to a suitable source of electricity (not shown).

Base 60 is normally and yieldingly coupled to sprocket wheels 59 by a spring detent arrangement 85 consisting of a section of vertical tubing 86 that carries a compression spring 87, which bears at its lower end against an adjusting screw plug 89 and at its upper end against a steel ball 88 for urging the ball into a recess or notch 90 in the under side of base 60.

An endless chain conveyor 91 is moved through lower compartment 25 of housing 10 along the tortuous path indicated by the arrows by means of a series of sprocket wheels 92 and 93. An electric motor 94 (Figure 3) drives endless conveyor 91 and rotary mechanisms 50 through suitable devices that will now be described. These devices include a vertical shaft 95 that is actuated by motor 94 through sprocket wheels 96 and 97 and a chain drive 98. Shaft 95 extends through an opening 99 in top wall 15 and has its lower end disposed in a bearing 100. One of the sprocket wheels 93 is affixed to the lower end portion of shaft 95 (Figure 2) and serves to actuate endless conveyor 91 upon rotation of shaft 95. The remaining sprocket wheels 93, as well as sprocket

wheels 92, are rotatably supported in any desired manner on stub shafts 101. A sprocket pinion 102 is affixed to each sprocket wheel 92, by welding or the like, for rotation therewith, and drives the corresponding sprocket wheel 59 through a chain drive 103 (Figure 4).

Endless conveyor 91 has secured thereto a series of spaced upstanding spindles or supports 104 which are preferably double frusto-conical in configuration. Each support 104 is provided with two series of spaced radial slots 105 and 106, slots 105 extending nearer the axis of the support than slots 106. Tubular bodies 48 after being sprayed in rotary mechanism 50 are placed over and adapted to be supported along their lower edges by supports 104. Radial slots 105 and 106 prevent the formation of beads of coating material on the interior of tubular bodies 48 as they serve to drain excess of the coating material by capillary action. A hollow cylindrical guard 107 (Figures 8 and 9), flared at its upper end, is disposed concentric with and spaced from each support 104 and is maintained in this position by legs 108 that are soldered or otherwise attached to endless conveyor 91. Each guard 107 is provided with a number of indentations or teats 109 which contact the outer surface of tubular bodies 48 should any of them tend to topple over in the course of their passage through housing 10.

During the operation of the above described devices, an operator stands in front of each rotary mechanism 50 and as endless belt passes by removes uncoated tubular bodies 48 from pins 47 and places them over the upper end of hollow arms 62. With the apparatus arranged, as illustrated and described, rotary mechanisms 50 will rotate in a clockwise direction as viewed in Figure 1. Therefore, the operator may remove individual tubular bodies 48 from pins 47 with his left hand and place them on hollow arms 62. In the course of rotation of mechanism 50 a quantity of the coating material, for example, wax in a liquid state, is sprayed into each tubular body 48 during a predetermined portion of each complete revolution of the base 60. Simultaneous with the injection of the liquid wax into an individual tubular body, the corresponding hood 74 will be positioned thereover. Hoods 74 prevent tubular bodies from being forced upwardly and off their arms during the coating operation. Additionally, should the operator fail to place a tubular body on one of the arms, the corresponding hood will be placed over the upper end of the arm and thus confine the sprayed wax, prevent the wax from being deposited on the exterior of adjacent tubes, and eliminate the possibility of injury to the operator. After the liquid wax is sprayed into a tubular body, the operator removes it from its supporting arm with his right hand and places it on a support 104 carried by an adjacent portion of endless conveyor 91. The conveyor then passes through lower compartment 25 where the heated air supplied through blower 27 maintains the wax above its melting point to insure excess being drained off by gravity and through the capillary action afforded by slots 105 and 106. As the endless belt emerges through the rear wall of housing 10 another operator removes each tubular body.

As was indicated above, excess coating material is drained from tubular bodies 48 in compartment 25. This excess material flows into sump 17 and is removed therefrom by devices which will now be described. These devices include a rotary pump 115, that has its inlet connected by

a conduit 116 to a strainer 117 which includes a cylindrical screen 118. Strainer 117 attached to the lower end of a rod 119 that is slidable through an opening 120 in a removable closure 121 and that carries an operating handle 122 at its upper end to permit of its ready insertion and removal as required through an opening 123 in perforate partition 22. Connected to rotary pump 115 is a combined hollow drive shaft and discharge conduit that is actuated by a motor 125. The liquid wax that collects in sump 17 is transmitted upwardly by pump 115 and through conduit 124 from whence it may be returned to the source of supply of liquid wax, or disposed of as desired.

An exhaust pipe 128 having a butterfly type of control valve 129 is carried by housing top wall 15. Also, a hood 130 is disposed over the portion of endless conveyor 91 that is exterior the rear wall 12. This hood has a flue 131 for removing undesirable fumes that may be evolved.

When the machine of our invention is out of service for any considerable period of time, the devices embodying rotary mechanism 50 tend to cool and the wax therein may become hardened. Electrical heating cartridge 81 serves to supply heat to the various parts of rotary mechanism 50, which are preferably metallic and thereby melt any wax that may have become solidified therein prior to placing the machine in service again.

From the foregoing, it is believed that the construction, operation and advantages of our present invention will be readily comprehended by persons skilled in the art. It is to be clearly understood, however, that various changes in the apparatus set forth above may be made without departing from the scope of the invention, it being intended that all matter contained in the description, or shown in the drawings shall be interpreted as illustrative only and not in a limiting sense.

We claim:

1. In apparatus of the character described, a stationary substantially upright hollow shaft, a base rotatable about the axis of said shaft, means for imparting rotation to said base, a plurality of spaced upstanding hollow arms carried by said base and disposed substantially equidistant from the axis of said shaft, and means communicating with the interior of said shaft for selectively and successively transmitting fluid material into the interior of each of said arms during a corresponding predetermined portion of each complete revolution of said base about said shaft, each of said arms having a plurality of passages establishing communication between the interior and exterior thereof and extending in a direction generally upward and at an acute angle to corresponding radii of said arms.

2. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, and means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base com-

municating with the interior of a corresponding arm, and means for successively placing said passage in said shaft in and out of fluid communication with each of said passages in said base during corresponding portions of each complete revolution of said base.

3. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, and means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means.

4. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, and means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means, said ports having their outer ends spaced peripherally and being formed in a manner to discharge said fluid material at an acute angle upwardly and laterally of corresponding radii of said arm.

5. In apparatus of the character described, an upright hollow shaft, a rotary base rotatable about the axis of said shaft, a plurality of spaced upstanding hollow arms carried by said base and disposed substantially equidistant from the axis of rotation thereof, a plurality of discharge ports in each arm establishing communication between the interior and the exterior thereof, means selectively and successively placing the interior of each of said arms into and out of communication with the interior of said hollow shaft during a corresponding predetermined portion of each complete revolution of said base, rotary driving means, and means normally and yieldingly coupling said driving means to said base.

6. In apparatus of the character described, an upright hollow shaft, a rotary base rotatable about the axis of said shaft, a plurality of spaced upstanding hollow arms carried by said base and disposed substantially equidistant from the axis

of rotation thereof, a plurality of discharge ports in each arm establishing communication between the interior and the exterior thereof, means selectively and successively placing the interior of each of said arms into and out of communication with the interior of said hollow shaft during a corresponding predetermined portion of each complete revolution of said base, rotary driving means, and means comprising a spring-pressed detent for normally and yieldingly coupling said driving means to said base.

7. In apparatus of the character described, a rotary base, a plurality of spaced upstanding hollow arms carried by and rotatable with said base, means for selectively transmitting fluid material into the interior of each of said arms during a corresponding predetermined portion of each complete revolution of said base, support means associated with and extending upwardly of said base, a hood adjacent each of said arms and pivotally connected to said support means, means comprising a single spring for normally and yieldingly urging each hood about its pivotal connection with said support means in a manner to move the same away from its corresponding arm during a predetermined portion of each complete revolution of said base, and means for urging each hood over the upper part of its corresponding arm against the action of said third mentioned means during the remainder of each complete revolution of said base.

8. In apparatus of the character described, a rotary base, a plurality of spaced upstanding hollow arms carried by and rotatable with said base, means for selectively transmitting fluid material into the interior of each of said arms during a corresponding predetermined portion of each complete revolution of said base, support means associated with and extending upwardly of said base, a hood adjacent each of said arms and pivotally connected to said support means, means comprising a single spring for normally and yieldingly urging each hood about its pivotal connection with said support means in a manner to move the same away from its corresponding arm during a predetermined portion of each complete revolution of said base, and means comprising a single cam for urging each hood over the upper part of its corresponding arm against the action of said third mentioned means during the remainder of each complete revolution of said base.

9. In apparatus of the character described, a substantially upright shaft, a base rotatable about the axis of said shaft, means for imparting rotation to said base, a plurality of spaced upstanding hollow arms carried by said base and rotatable therewith, means for selectively transmitting fluid material into the interior of each of said arms during a corresponding predetermined portion of each complete revolution of said base, each of said arms having a plurality of passages in its upper part for discharging fluid material admitted thereto by said last mentioned means, support means secured to and rotatable with said base, a hood having an open end adjacent each of said arms, and means for positioning and maintaining each hood over the upper part of its corresponding arm so that the open end thereof extends below said upper part of its corresponding arm during a predetermined portion of each complete revolution of said base and for moving each hood away from the upper part of

its corresponding arm during the remainder of each complete revolution of said base.

10. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means, support means secured to and rotatable with said base, a hood adjacent each of said arms and pivotally connected to said support means, means for urging each hood about its pivotal connection with said support means in a manner to move the same away from its corresponding arm during a predetermined portion of each complete revolution of said base, and means for urging each hood over the upper part of its corresponding arm during the remainder of each complete revolution of said base.

11. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means, a support secured to and rotatable with said base, a hood adjacent each of said arms and pivotally connected to said support, means for normally and yieldingly urging each hood about its pivotal connection with said support in a manner to move the same away from its corresponding arm during a predetermined portion of each complete revolution of said base, and means for urging each hood over the upper part of each arm against the action of said last mentioned means during the remainder of each complete revolution of said base.

12. In apparatus of the character described, a stationary substantially upright shaft, a base rotatable about the axis of said shaft, means for imparting rotation to said base, a plurality of spaced upstanding hollow arms carried by said base and disposed substantially equidistant from

the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means, a support secured to and rotatable with said base, a hood adjacent each of said arms and pivotally connected to said support, means for normally and yieldingly urging each hood about its pivotal connection with said support in a manner to move the same away from its corresponding arm during a predetermined portion of each complete revolution of said base, and means comprising a cam for urging each hood over the upper part of each arm against the action of said last mentioned means during the remainder of each complete revolution of said base.

13. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said passage in said shaft in and out of fluid communication with each of said passages in said base during corresponding portions of each complete revolution of said base, each of said arms having a plurality of ports for discharging fluid material admitted thereto by said second mentioned means, a support secured to and rotatable with said base, a hood adjacent each of said arms and pivotally connected to said support, means comprising a single spring for normally and yieldingly urging each hood about its pivotal connection with said support in a manner to move the same away from its corresponding arm during a predetermined portion of each complete revolution of said base, and means comprising a single cam for urging each hood over the upper part of each arm against the action of said last mentioned means during the remainder of each complete revolution of said base.

14. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said

15. In apparatus of the character described, a stationary substantially upright shaft, a base rotatable about the axis of said shaft, means for imparting rotation to said base, a plurality of spaced upstanding hollow arms carried by said base and disposed substantially equidistant from the axis of said shaft, means for selectively and successively transmitting fluid material into the interior of each of said arms during a corresponding predetermined portion of each complete revolution of said base about said shaft, said last mentioned means comprising a passage in said shaft, a plurality of passages in said base, each of said plurality of passages in said base communicating with the interior of a corresponding arm, and means for successively placing said 20 passage in said shaft in and out of fluid communication with each of said passages in said base during corresponding portions of each complete revolution of said base, each of said arms having a plurality of ports for discharging fluid material admitted thereto by said second mentioned means, a support secured to and rotatable with said base, a hood adjacent each of said arms and pivotally connected to said support, means comprising a single spring for normally and yieldingly urging each hood about its pivotal connection with said support in a manner to move the same away from its corresponding arm during a predetermined portion of each complete revolution of said base, and means comprising a single cam for urging each hood over the upper part of each arm against the action of said last mentioned means during the remainder of each complete revolution of said base.

16. In apparatus of the character described, an upstanding hollow arm having a plurality of passages establishing communication between the interior and the exterior thereof, said passages being spaced apart and extending in a direction generally upward and at an acute angle to a corresponding radius of the arm.
